Inventor:
Robert T. Davis

by M. Harrison
Attorney.

UNITED STATES PATENT OFFICE.

ROBERT T. DAVIS, OF NASHUA, NEW HAMPSHIRE, ASSIGNOR TO NASHUA PACKAGE SEALING CO., INC., OF NASHUA, NEW HAMPSHIRE, A CORPORATION OF MASSACHUSETTS.

GUMMED-TAPE MOISTENER.

Application filed October 20, 1924. Serial No. 744,679.

To all whom it may concern:

Be it known that I, ROBERT T. DAVIS, a citizen of the United States, and resident of Nashua, in the county of Hillsboro and 5 State of New Hampshire, have invented certain new and useful Improvements in Gummed-Tape Moisteners, of which the following is a specification.

This invention relates to devices for applying moisture to strips of dry-gummed paper or cloth to prepare the strips for application to bundles or packages, and has particular reference to that type of such devices which support a coil of the gummed 15 tape in convenient position for a user to draw off a desired length of the tape which, as it is drawn, passes over a moistening pad.

The principal object of my invention is to provide devices of this character which 20 are simple in construction and capable of production at minimum cost. In addition to attaining this object, my invention enables the moisteners to be produced in practical form without including any parts that will get out of order or require adjustment.

Of the accompanying drawings:—

Figure 1 is a perspective view of one of my improved moisteners, with a coil of gummed tape in the position which it occupies when ready for use.

Figure 2 is a plan view of the moistener, omitting the coil of tape.

Figure 3 represents a section on line 3—3 of Figure 2.

Similar reference characters indicate similar parts in all of the views.

With the exception of the cup for the moistening pad, the entire device comprises a single strip or sheet of steel or other suitable metal bent to form a plate or table 12 having legs 13, the latter having, when desired, flanges to form feet 14 which may have screw holes to enable the device to be secured to a counter or table, or elsewhere, 40 when fixed position is preferable. The plate 12 is provided with a coil-supporting depression by forming two longitudinal slits therein and transversely severing the portion between such slits and bending the 45 metal down to form an inclined member 15 hereinafter referred to as the tongue and a short lip 16 opposite the end of the tongue.

Near the higher end of the tongue the plate is formed with two transverse slots 50 between which is a bar 17 capable of being

bent to occupy a plane more or less above the plane of the plate, or below it, when desired, for a purpose explained hereinafter.

A cup 18, for holding a moistening pad 19 of felt or other suitable material, is fitted to a hole formed in the plate 12. Said cup may be removable to facilitate cleaning it. Adjacent the moistening pad the plate is formed with integral teeth 20 preferably rising from the angle between the plate and the leg 13 at that end of the device, to enable the strip *a* of gummed tape to be carried down alongside of that leg when it is to be severed as presently described.

When the device is to be used, a coil *a'* 70 of gummed tape is placed on the tongue 15 as indicated by Figure 1. It will automatically retain the position illustrated, its proper lateral position being maintained by the edges of the slot formed when the tongue was cut. The end of the tape *a* is passed under the tension bar 17 and left free. It is then ready for use. When a certain length of moistened tape is wanted, the user grasps the free end of the tape and pulls it

in a direction that will cause its under surface which, of course, is the gummed surface, to slide in contact with the moistening pad 19. When the length desired has been so drawn, the user simply pulls in a downward direction so that the teeth 20 will first puncture the tape and then cause its severance. It is not necessary to bear on or otherwise hold the strip at a point behind 80 the pad because the tension bar 17 serves

to hold the strip against longitudinal movement when said strip is being severed in the manner described. This holding is due to the strip passing down through one slot and up through the other slot at opposite sides of the bar 17. If the strip is a thick one and the friction of the tension bar is too great to render the strip to be fed readily when pulled over the moistening pad, the bar 17 may be bent up somewhat to relieve the tension, and if the strip pulls too easily, said bar may be bent down below the plane of the plate to increase the tension. The slots at opposite sides of the bar 17 serve to guide the strip, and the bar coacts with said slots in maintaining the strip *a* always in position ready to be pulled when desired.

In connection with the fact that strip *a* normally projects beyond the moistening pad, it will be readily understood that if a

user wishes to have that portion moistened, he can slide that portion back over the pad before pulling, or can, after pulling and severing, turn the severed length around and moisten the end which was the front end. If said front end is slid back over the pad before pulling, the user can, if he wishes, stick that front end to the package which is to be secured by the strip, and then hold said front end pressed against the package while pulling the rest of the length desired.

10 The device as a whole is not only simple and of low cost, but is very compact. A shallow box will contain it, and if it is desired to place a coil of tape also in such box, said coil will lie flat under the plate.

15 Having now described my invention, I claim:—

20 1. A device of the character described, comprising a support for a coiled strip, a tension device for the strip, a severing means for the strip, and means for moistening the strip, all of said parts excepting the moistening means being formed of one piece of sheet metal.

25 2. A gummed tape moistener having a single flat horizontal plate provided with a

depressed portion for a coil of tape and also having strip severing means and a strip tension bar intermediate said depressed portion and the severing means.

3. A gummed tape moistener having a coil supporting plate provided with strip-guiding slots and an integral strip-tensioning bar.

4. A gummed tape moistener having a slotted plate with an integral tongue inclined downwardly in the slot to form a coil support, and a tension bar and strip-severing teeth integral with said plate.

5. A gummed tape moistener having a strip-tension device and a strip moistener and strip-severing means in substantially a single horizontal plane.

6. A device of the character described, comprising a single strip of metal having a horizontal portion provided with a depression to hold a roll of gummed tape, the said strip being bent to provide legs at the ends of the horizontal portion, a moistening device being carried by the said horizontal portion.

In testimony whereof I have affixed my signature.

ROBERT T DAVIS.
